ROTARY COMPRESSOR

Paul August, Capellades 1, Barcelona 6, Spain
Filed Mar. 8, 1965, Ser. No. 437,956
Claims priority, application Germany, Mar. 11, 1964,
J 25,422
14 Claims. (Cl. 230—147)

My present invention relates to certain new and useful improvements in rotary compressors comprising a gyroscopic displacer operated by a driving shaft with the interposition of an eccentric.

The main object of the invention is to improve the efficiency and the antifrictional conditions of said rotary compressors by eliminating abrasion-causing oscillations of the driving shaft and of the gyroscopic displacer and by providing a continuously renewed oil film on contacting or adjacent parts of the compressor, said oil film providing not only for a good lubrication and efficient sealing of the compressor, but also a distancing means between adjacent parts of the same.

The improved rotary compressor according to the invention comprises a cylindrical casing, a central driving shaft rotatively mounted in the end walls of said casing, an eccentric fixed on said shaft in said casing, at least one cavity formed in said eccentric in its portion of larger extension, bearing means arranged on said eccentric for a cylindrical displacer, at least one annular cavity formed by said eccentric and within said displacer, a flywheel mass on said shaft in a portion of said annular cavity diametrically opposite said first-mentioned cavity for substantially balancing said portion of larger extension of the eccentric, a rib member radially projecting from said displacer into a recess provided in said casing, this recess forming near the inner wall of said casing a pair of opposite semi-cylindrical grooves for containing corresponding rotary guide members between which said rib member projects into a compression chamber formed by said recess beyond said grooves, said rib member acting as a pump piston in said compression chamber, air conducting means connecting said compressor chamber with an oil supply means and duct means from said oil supply means to an oil spray distribution system for producing a lubricating, sealing and distancing oil film under pressure between component parts of the compressor.

The arrangement of the flywheel mass conveniently in such that the eccentric between its end portions which carry the bearings of the gyroscopic displacer provides for an annular cavity and that in this cavity at the side of its shorter extension the flywheel mass is fixed to the driving shaft. The arrangement may also be such that only one bearing is provided in the middle of the eccentric and that the end portions of the latter form the cavities for two flywheel masses secured to the driving shaft. If required, the said cavities for the flywheel masses may be enlarged by inner recesses of the displacer body. In certain cases the cavity or cavities for housing the flywheel mass or masses may be formed in their major part in the displacer body. The displacer in one or both end portions may be provided with annular recesses for facilitating the assembling of the eccentric, flywheel mass, bearings and displacer on the driving shaft within the compressor casing.

For the continuous production of the oil film, in my U.S. patent specification No. 3,116,012 I have described a lubricating pump system comprising a recess in the cylindrical wall of the compressor casing, wherein the rib member of the gyroscopic displacer acts as a pump piston, an oil container provided in the base or support of the compressor and having a wick which projects into a duct connected with said recess.

In accordance with the present invention, as already

2

stated, the said recess or compression chamber of the pump forms adjacent the inner wall of the cylindrical compressor casing a pair of opposite semi-cylindrical grooves for housing a pair of corresponding guide members for the rib member of the gyroscopic displacer, and each of these guide members is provided with a central longitudinal bore and with a number of radial branch channels leading to the surfaces of the guide member, so that the oil-carrying air operated by said lubricating pump is delivered not only to the surfaces of said guide members contacting said rib member and the walls of said grooves, but also into the proper compressor casing wherein it thus also produces a lubricating as well as sealing oil film.

Thus according to the invention the combination of the balanced eccentric, on the one hand, and the lubricating and sealing oil film, on the other hand, permits to obtain a smooth operation of the compressor without a direct wearing contact of the compressor parts and with an effective sealing effect between the suction side and the pressure side the same economic compression in one stage as achieved in the known compressors using a reciprocating piston. Further, the oil film which according to the invention is not only continuously renewed, but is also maintained under certain pressure, constitutes a distancing means between the displacer and the walls of the compressor casing with the advantageous result that the improved compressor complies with the desired requirements of high antifrictional quality, of a minimum rate of wear and tear and of a maximum efficiency and output.

With this object in view, the present invention further proposes the provision of additional oil spray ducts in form of straight longitudinal grooves in the end surfaces of the rib member of the displacer and in form of annular grooves in the end surfaces of the cylindrical displacer, these annular grooves being in communication with said straight grooves. In this manner the end walls of said rib member and of the displacer are directly included in the oil spray distribution system. In this arrangement the said compression chamber formed by the recess of the compressor casing may be connected by way of channels with the said grooves in the end surfaces of the rib member which in turn as stated are in direct communication with the said annular grooves in the end surfaces of the displacer. The arrangement may also be such that the said grooves in the end surfaces of the rib member are in direct communication with the said compression chamber. Further, the arrangement may be such that channels connecting the compression chamber with the grooves in the end surfaces of the rib member are provided in the walls of the compressor casing or alternatively in the rib member itself. In this latter case these channels in the rib member are conveniently in direct communication with the grooves in the end surfaces of the rib member and by way of these grooves with the annular grooves in the end walls of the displacer.

The intake opening of the compression chamber of the lubricating pump is provided with a nonreturn valve; a like valve may be provided between said chamber and the oil spray distribution system.

The oil container, instead of being arranged in the base or support of the compressor, may also be disposed at any other place, for instance, near the compression chamber of the lubricating pump e.g. in the end walls of the compressor casing. On the other hand, the wick or wicks of the oil container or containers may be elongated up to a level of the said compression chamber so as to advantageously shorten the circuit of the oil-carrying air current.

An important feature of the invention consists in that

the rib member and the compression chamber are of such dimensions that the oil spray is injected into the distribution system under certain pressure capable of maintaining the oil film as a distancing means between the displacer and the compressor casing.

The compressor will now be described in detail with reference to the accompanying drawings showing by way of example in

FIG. 1 a schematic cross sectional view of the improved rotary compressor according to the invention;

FIG. 2 a schematic sectional view of the displacer, bearings and eccentric on a plane perpendicular to that of FIG. 1;

FIG. 3 a front view of the compressor according to FIGURES 1 and 2 without the respective end wall;

FIG. 4 a longitudinal sectional view of the compressor according to FIG. 3;

FIG. 5 a cross sectional view of a modified embodiment of the compressor according to the invention;

FIG. 6 a longitudinal sectional view on a plane perpendicular to that of FIG. 5, and

FIG. 7 a fragmentary cross sectional view of a further modified embodiment of the compressor according to the invention.

Having reference to the accompanying drawings, the rotary compressor comprises a cylindrical casing 1 with a central driving shaft 2 rotatively mounted in the end walls 31 (FIG. 4) of said casing. An eccentric 3 is fixed to the shaft 2 and carries the bearings 5 which in turn carry the cylindrical displacer 8. The eccentric 3 in its portion of larger extension—with regard to the shaft 2—is provided with cavities 4 for reducing the weight of this eccentric portion. In addition hereto the eccentric between its end portions which carry the bearings 5 forms an intermediate annular cavity 6. In this cavity 6 at the side of the shaft 2 opposite the first-mentioned cavities 4 a flywheel mass 7 is fixed to the driving shaft 2 as shown in FIG. 1 for balancing the eccentric and eliminating oscillations of said shaft due to a centrifugal force likely to be produced by an unbalanced eccentric. In order to provide for sufficient free space for the flywheel mass 7, the displacer 8 is conveniently provided with a corresponding recess as indicated at 9.

For mounting the eccentric 3, the flywheel mass 7, the bearings 5 and the displacer 8 on the driving shaft 2 within the casing 1, the displacer 8 is provided at least at one end with an annular cavity of a diameter corresponding to that of the recess 9, which is engaged and filled conveniently by a corresponding annular projection 10 of the respective end wall of the compressor casing.

The displacer 8 is provided as usually with a radially projecting rib member 11 extending into a recess of the casing 1 and separating the suction side from the pressure side of the compressor i.e. the intake opening 13 from the outlet opening 14. The outlet opening 14 comprises a nonreturn valve 32 (FIG. 4). The intake opening 13 is conveniently provided with an air filter 33. The said recess of the casing 1 forms near the inner wall of the latter a pair of opposite semi-cylindrical grooves for containing a pair of correspondingly shaped guide members 12 between which the guide members 11 slides in reciprocating motion and acts as a pump piston in a compression chamber 19 formed in an extension of the casing 1 beyond said semi-cylindrical grooves. Each of the guide members is provided with a central longitudinal bore 18 and with a number of branch channels 21 leading from said bore to the outer surfaces of the guide members 12.

For a good operation and high efficiency of the rotary compressor its antifrictional quality has to be achieved to the highest possible degree. This, however, can not be attained alone by eliminating the oscillations of the driving shaft together with the compressor parts mounted thereon. A good lubricating, sealing and distancing oil film on and between adjacent compressor parts is abso-

lutely necessary in combination with the feature of balancing the eccentric.

For this purpose, the pump constituted by the rib member 11 as a pump piston and by the recess 19 as a compression chamber, according to the invention is provided with an improved distribution system for the oil-carrying air or oil spray supplied by said pump. This distribution system in the first instance comprises the above-mentioned bores 18 with their branch channels 21 in the guide members 12. The rib member in its downward movement by way of the intake duct 34 (FIG. 4) sucks air into the compression chamber 19 and in its upward movement delivers the air by way of a duct 15 conveniently provided with a nonreturn valve 20 (FIG. 1) to a duct 16. This duct 16 may be a bore in the casing 1 which as shown in FIG. 4 in form of a duct 161 leads upwards again to the level of the rib member 11 where it establishes a connection with the bores 18 of the guide member 12. A wick 17 provided in an oil container 21 projects into said duct 16 and continuously delivers lubricating oil to the air current produced by said pump and circulated through the ducts 15, 16, 161 and to be injected into said bores 18 and branch channels 21. The arrangement of these branch channels is such that the major part of the oil spray is supplied to the surfaces of the guide members 12 contacting the side walls of the rib member 11. As this rib member slides up and down, certain part of the oil spray enters the compressor and the rest is delivered to the outer surfaces of the guide members 12. In view of the fact that during operation of the compressor and therewith of the pump 11, 19 the supply of oil spray continues and produces a continuously renewed oil film on the rib member 11 and its guide members 12 as well as on the displacer 8 and the inner walls of the casing 1, this oil film has not only a perfect lubricating and sealing effect of the rib member which separates the suction side from the pressure side of the compressor with the result that its efficiency is increased, but also acts as a distance means between the surfaces of the displacer and the inner walls of the compressor casing which assists in avoiding wear and tear and in prolonging the lifetime of the compressor. As practice has taught the oil spray even reaches the bearings 5 and takes charge of its permanent lubrication.

In as far as the oil film as distance means is concerned, experiments proved that even in the case of a flywheel mass being provided for balancing the eccentric and the displacer oscillation or vibration of the latter may occur in dependence of the rotation speed and may produce contacts of the displacer with the inner wall of the cylindrical casing. Therefore, a clearance between the displacer and the casing walls which, however, affects the efficiency of the compressor, is necessary and this clearance has to be filled by a sealing and distancing oil film i.e. an oil film produced and maintained under pressure. For this purpose the dimensions of the pump 11, 19 and the nonreturn valve 20 are to be elected in such a manner that the oil spray is delivered under pressure.

The compression chamber 19 by way of a nonreturn valve 20 may be directly connected with the atmosphere or as shown in FIG. 5 by means of a duct 34 with the air filter 33 of the compressor.

In the embodiments of the invention as shown in FIGURES 5 to 7, the end surfaces of the rib member 11 are provided with straight longitudinal grooves 22 which are in direct communication with annular grooves 23 (FIGURES 5 and 6) cut into the end surfaces of the gyratory displacer 8.

There are different possibilities of including the grooves 22 and 23 in the circuit of the oil spray current. In a preferred embodiment as shown in FIG. 6, the compression chamber 19 is in communication by way of the nonreturn valve 20 with a cross channel 35 which in turn communicates with a pair of ducts 24 and 25 provided in

the walls of the compressor casing. These ducts 24 and 25 establish the connection with the straight grooves 22 in the end surfaces of the rib member 11 and by way of branch channels as indicated at 36 with the longitudinal bores 18 of the guide members 12.

Into the ducts 24 and 25 project the upper ends of the wicks 17 which extend from the oil container 21 along corresponding channels provided in the end walls of the compressor casing so as to supply the lubricating oil to the air current produced by the pump 11, 19, the non-return valve 20 being so arranged that by the downward stroke of the rib member 11 air is sucked in by way of the air intake 34 and not by way of the channel 35 and ducts 24, 25. The air intake 34 may be connected as shown in FIG. 5 with the air filter of the compressor or with the atmosphere as shown in FIG. 7.

Instead of providing the oil container in the base or support of the compressor, an oil container may be arranged in each of the end walls of the compressor casing with the advantageous result that the oil spray current produced by the pump 11, 19 is shortened. In this arrangement, if desired, the wicks 17 may be dispensed with and the ducts 24, 25 may be in communication by way of suitable nozzles with the respective oil containers provided in the end walls of the compressor casing.

Another embodiment has been simultaneously shown in FIG. 6, comprising a pair of channels 26 in the rib member 11 and connecting the compression chamber 19 by way of the nonreturn valve 27 with the straight longitudinal grooves 22 in the end surfaces of the rib member 11. The valve 27 is destined for preventing the oil spray from being sucked back through the channels 26 into the compression chamber 19.

During operation of the compressor and therewith of the pump piston 11 an oil spray is continuously pressed into the grooves 22 and 23. As the valves 20 and/or 27 prevent the oil spray from flowing back, in said grooves 22 and 23 certain pressure is produced which, on the one hand, takes care of forming an efficiently sealing oil film between the end surfaces of the displacer and the end walls of the compressor casing and on, the other hand, causes this oil film to form a distance means between the end walls of the compressor casing and the end surfaces of the displacer. According to its size the displacer is arranged with regard to the end walls of the compressor casing so as to provide a clearance of $\frac{5}{100}$ to $\frac{1}{10}$ mm. which is effectively filled by the said oil film, with the advantageous result that the oil film under pressure is really capable of providing a distance means. In view of the fact that in each case the longitudinal bores 18 and the radial branch channels 21 of the guide members 12 are included in the circuit of the oil spray current, said guide members 12 as well as the rib member 11 are also provided with a lubricating and sealing oil film which is permanently renewed and maintained under pressure. The oil spray which reaches the interior of the compressor is quantitatively so small as compared the quantity of air which the compressor sucks in by way of the filter 33 and pushes out by way of the outlet 14 that a contamination of the compressed air does not occur.

On the other hand, it is important to construct the pump 11, 19 of such dimensions that its output is high to produce the desired pressure in the circuit of the oil spray current.

In the embodiment as shown in FIG. 7, the grooves 22 in the end surfaces of the rib member 11 reach the upper end of the latter and thus are in direct communication with the compression chamber 19. In this case, too, the grooves 22 of the end walls of the compressor casing are in communication with the annular grooves 23 of the displacer 8. The compression chamber 19 has an air intake 34 provided with a nonreturn valve 20 and connected with the atmosphere or with the oil filter of the compressor. According to this embodiment the wick projects directly into the intake 34, whereby the con-

struction of the compressor is simplified, particularly if the oil container is arranged somewhere adjacent the extension of the casing 1 which forms the recess for the rib member 11 and the compression chamber 19.

5. What I claim is:

1. A rotary compressor, comprising a cylindrical casing, a central driving shaft rotatively mounted in the end walls of said casing, an eccentric fixed on said shaft in said casing, at least one cavity formed in said eccentric in its portion of larger extension, bearing means arranged on said eccentric for a cylindrical displacer, at least one annular cavity formed by said eccentric, and within said displacer a flywheel mass on said shaft in a portion of said annular cavity diametrically opposite said first-mentioned cavity for substantially balancing said portion of larger extension of the eccentric, a rib member radially projecting from said displacer into a recess provided in said casing, this recess forming near the inner wall of said casing a pair of opposite semi-cylindrical grooves for containing corresponding rotary guide members between which said rib member projects into a compression chamber formed by said recess beyond said grooves, said rib member acting as a pump piston in said compression chamber, air conducting means connecting said compression chamber with an oil supply means and duct means from said oil supply means to an oil spray distribution system for producing a lubricating, sealing and distancing oil film under pressure between component parts of the compressor.
2. A rotary compressor, comprising a cylindrical casing, a central driving shaft rotatively mounted in the end walls of said casing, an eccentric fixed on said shaft in said casing, at least one cavity formed in said eccentric in its portion of larger extension, bearing means arranged on said eccentric for a cylindrical displacer, an annular cavity formed by said eccentric at each end thereof and at each side of an intermediate portion of said eccentric carries said bearing means for said displacer, a flywheel mass provided on said shaft in a portion of each of said annular cavities diametrically opposite said first-mentioned cavity for substantially balancing said portion of larger extension of the eccentric, a rib member radially projecting from said displacer into a recess provided in said casing, this recess forming near the inner wall of said casing a pair of opposite semi-cylindrical grooves for containing corresponding rotary guide members between which said rib member projects into a compression chamber formed by said recess beyond said grooves, said rib member acting as a pump piston in said compression chamber, air conducting means connecting said compression chamber with an oil supply means and duct means from said oil supply means to an oil spray distribution system for producing a lubricating, sealing and distancing oil film under pressure between component parts of the compressor.
3. A rotary compressor, comprising a cylindrical casing, a central driving shaft rotatively mounted in the end walls of said casing, an eccentric fixed on said shaft in said casing, at least one cavity formed in said eccentric in its portion of larger extension, bearing means arranged on said eccentric for a cylindrical displacer, at least one annular cavity formed by said eccentric, and within said displacer a flywheel mass on said shaft in a portion of said annular cavity diametrically opposite said first-mentioned cavity and in a recess of said displacer in alignment with said annular cavity of said eccentric for substantially balancing said portion of larger extension of the eccentric, a rib member radially projecting from said displacer into a recess provided in said casing, this recess forming near the inner wall of said casing a pair of opposite semi-cylindrical grooves for containing corresponding rotary guide members between which said rib member projects into a compression chamber formed by said recess beyond said grooves, said rib member acting as a pump piston in said compression chamber, air conducting means connecting said compression chamber with an

oil supply means and duct means from said oil supply means to an oil spray distribution system for producing a lubricating, sealing and distancing oil film under pressure between component parts of the compressor.

4. A rotary compressor, comprising a cylindrical casing, a central driving shaft rotatively mounted in the end walls of said casing, an eccentric fixed on said shaft in said casing, at least one cavity formed in said eccentric in its portion of larger extension, bearing means arranged on said eccentric for a cylindrical displacer, an annular cavity formed by said eccentric at each end thereof and at each side of an intermediate portion of said eccentric which carries said bearing means for said displacer, a flywheel mass provided on said shaft in a portion of each of said annular cavities diametrically opposite said first-mentioned cavity and in corresponding recesses of said displacer in alignment with said annular cavities of said eccentric for balancing said portion of larger extension of said eccentric, a rib member radially projecting from said displacer into a recess provided in said casing, this recess forming near the inner wall of said casing a pair of opposite semi-cylindrical grooves for containing corresponding guide members between which said rib member projects into a compression chamber formed by said recess beyond said grooves, said rib member acting as a pump piston in said compression chamber, air conducting means connecting said compression chamber with an oil supply means and duct means from said oil supply means to an oil spray distribution system for producing a lubricating, sealing and distancing oil film under pressure between component parts of the compressor.

5. A rotary compressor as set forth in claim 4, wherein the said displacer is provided at least at one end with an annular recess for facilitating the operation of mounting the said eccentric, the said flywheel masses and said displacer on the said driving shaft, said annular recess being capable of receiving a corresponding annular projection of the respective end wall of the compressor casing.

6. A rotary compressor, comprising a cylindrical casing, a central driving shaft rotatively mounted in the end walls of said casing, an eccentric fixed on said shaft in said casing, at least one cavity formed in said eccentric in its portion of larger extension, bearing means arranged on said eccentric for a cylindrical displacer, at least one annular cavity formed by said eccentric and within said displacer a flywheel mass on said shaft in a portion of said annular cavity diametrically opposite said first-mentioned cavity for substantially balancing said portion of larger extension of the eccentric, a rib member projecting radially from said displacer into a recess provided in said casing, this recess forming near the inner wall of said casing a pair of opposite semi-cylindrical grooves for containing corresponding rotary guide members between which said rib member projects into a compression chamber formed by said recess beyond said grooves, said rib member acting as a pump piston in said compression chamber, an air duct provided with a nonreturn valve and leading to an oil supply means constituted by a wick of an oil container and from there back to the level of said recess of the compressor casing, where it establishes communication with a longitudinal bore in each of said guide members and by way of said bores with radial branch channels leading to the outer surfaces of said guide members. These ducts, bores and channels forming part of an oil spray distribution system for producing a lubricating, sealing and distancing oil film under pressure between component parts of the compressor.

7. A rotary compressor as set forth in claim 6, wherein the said oil spray distribution system comprises additional oil spray ducts in form of straight longitudinal grooves cut into the end surfaces of the said rib member and in

form of annular grooves in the end surfaces of the said displacer.

8. A rotary compressor as set forth in claim 6, wherein the said oil spray distribution system comprises additional oil spray ducts in form of straight longitudinal grooves in the end surfaces of the said rib member and in form of annular grooves in the end surfaces of the said displacer in direct communication with said straight grooves, and channels provided in the walls of the compressor casing connecting said straight grooves and thereby said annular grooves with the said compression chamber.

9. A rotary compressor as set forth in claim 6, wherein the said oil spray distribution system comprises additional spray ducts in form of straight longitudinal grooves

15 in the end surfaces of the said rib member, which at their upper ends are in direct communication with the said compression chamber and at their lower ends with annular grooves in the end surfaces of the said displacer.

20 10. A rotary compressor as set forth in claim 6, wherein in the said oil spray distribution system comprises additional oil spray ducts in form of straight longitudinal grooves in the end surfaces of the said rib member and in direct communication therewith annular grooves in 25 the end surfaces of the said displacer, and a pair of channels in said rib member connecting said straight longitudinal grooves with the said compression chamber with the interposition of a nonreturn valve.

30 11. A rotary compressor as set forth in claim 6, wherein in the said oil spray distribution system comprises additional oil spray ducts in form of straight longitudinal grooves in the end walls of the said rib member and in direct communication therewith annular grooves in the end surfaces of the said displacer, channels provided in 35 the walls of the compressor casing connecting said straight grooves and thereby said annular grooves with the said compression chamber, and a pair of wicks extending from an oil container through corresponding channels in the end walls of the compressor casing into 40 said first-mentioned channels which connect said straight grooves with said compression chamber.

12. A rotary compressor as set forth in claim 6, wherein in the said air duct provided with a nonreturn valve is connected with the atmosphere.

45 13. A rotary compressor as set forth in claim 6, wherein in the said air duct provided with a nonreturn valve is connected with the air filter of the compressor.

14. A rotary compressor as set forth in claim 6, wherein in the said air duct provided with a nonreturn valve and leading to an oil supply means has a wick of an oil container constituting said oil supply means projecting into 50 said air duct between the said compression chamber and an air filter of the compressor.
